Patented May 30, 1922.

UNITED STATES PATENT OFFICE.

EDWARD H. SACKETT, OF ARVADA, COLORADO.

AERIAL TRAMWAY GRIP.

1,417,572.

Specification of Letters Patent. Patented May 30, 1922.

Application filed March 10, 1921. Serial No. 451,320.

To all whom it may concern:

Be it known that I, EDWARD H. SACKETT, a citizen of the United States, residing at Arvada, county of Jefferson, and State of Colorado, have invented certain new and useful Improvements in Aerial Tramway Grips; and I do declare the following to be a full, clear, and exact description of the invention, such as will enable others skilled 10 in the art to which it appertains to make and use the same, reference being had to the accompanying drawings, and to the characters of reference marked thereon, which form a part of this specification.

15 The object of this invention is to provide a grip for aerial tramways which is capable of adjustment and may be positively operated and securely retained.

Briefly, the invention comprises a block or 20 casing on which is mounted a fixed jaw, and in which a movable jaw slides, the movable jaw being adapted to be forced into clamping engagement by means of a toggle connection operated by a handle, the toggle being 25 adjustable by means of an eccentric mounting in order to engage cables of various sizes.

In the drawings:

Fig. 1 is a face view of the grip, as indicated by the arrow 1 of Fig. 2;

Fig. 2 is a vertical section taken on the line 2—2 of Fig. 1;

Fig. 3 is a cross section taken on line 3—3 of Fig. 2;

Fig. 4 is a sectional detail taken on the line 4 of Fig. 2;

Fig. 5 is a sectional detail taken on the line 5—5 of Fig. 1; and

Fig. 6 is a detail taken on the line 6—6 of Fig. 5, but showing the handle at the limit of its movement.

The grip is composed of a block or casting having two spaced arms 10 which comprise the sides of the block, the upper ends 45 of said arms being connected by means of a head 12 and the lower ends of said arms at the rear thereof being connected by means of a web or back-plate 14 carrying a hub or boss 15 to co-operate with any suitable 50 means for connecting with a bucket, such as a bolt 16 and a plate 18. The forward portions of the two arms 10 are cut away, as indicated in Figures 2 and 3, to provide forwardly facing shoulders 20 and upwardly 55 facing shoulders or ledges 22. A fixed jaw 24 is placed in engagement with said shoul-

ders 20 and 22 and clamped in said position by means of a plate 25 and screws 26, the plate spanning the two arms 10 so as to bind the jaw 24. A movable jaw 28 is also positioned against said shoulders 20 and is provided with an upwardly and rearwardly extending portion 128 which lies between the arms 10 at the rear of the shoulders 20. The extreme rear portion of the part 128 60 carries a pair of spaced ears 30 having projecting tongues extending laterally into guiding grooves 32 cut into the opposing walls of said arms 10. A spring 34 is connected with the top of the extension 128 of 65 jaw 28 and with the arms 10 by means of a pin 31, this spring being provided for the purpose of elevating the jaw 28. The jaw is also provided with elevating means in the form of a toggle connection comprising a 70 lower member 35 pivotally connected with an upper member 36, as indicated at 38, said lower member 35 being pivotally connected with the jaw 28, as indicated at 40. The upper end of the member 36 of the toggle 75 is pivoted upon a pin 42 eccentrically mounted in a pair of aligned sleeves 44 and 45 provided on the opposite sides of the upper end of the member 36. The sleeve 44 may be integrally connected with a yoke 46 80 and the sleeve 45 is carried by a plate 47 which is bolted at 48 to the end of the yoke 46 opposite from the sleeve 44. The yoke 46 has an upwardly directed extension 146 in the form of a tubular housing which receives 85 a locking pin 50, whose upper end is reduced to receive thereabout a spring 54 which normally urges the pin 50 downward. The upper reduced end 52 of said pin 50 projects through the housing 146 at the top thereof 90 and through an outer operating sleeve 55 to which it is connected, as indicated at 56. By lifting the sleeve 55 upward against the tension of the spring 54, the pin 50 may be withdrawn from one of the notches 58 in 95 the top of the head 12 to permit swinging of the yoke 46 in either direction, as indicated by the arrows in Fig. 1, so as to be adjusted in another of said notches, said sleeves 44 and 45 pivoting within the bore in the 100 head 12. The head 12 is cut away on each side of the upper member 36 of the toggle, as indicated at 43 in Figs. 1 and 4, to permit 105 swinging of said toggle member.

For the purpose of operating the toggle 110 to raise and lower the upper jaw 28, the upper member 36 is provided with a later-

ally disposed extension 136 to which there is pivoted at 60 a short link 62, which extends laterally to a point beyond the casing 10 where it is pivoted at 64 between and to two spaced jaws 65 integral with and operable by a handle 66. One jaw 65 has a laterally extending pivoting stem 68 which projects into a laterally extending ear 110 on the adjacent arm 10 of the casing, the extremity 10 of the stem 68 being secured in said ear 110, as shown at 70. The spaced jaws 65 provide between them a groove which receives the link 62, the bottom 67 of said groove constituting a stop-wall for the lower edge 15 of said link 62. The centers of the pivoting points 60, 65 and 68 are so arranged with relation to said stop-wall 67 that when the handle 66 is swung to lowermost position, as indicated in Fig. 6, the center of pivot 64 20 will lie below the dead center of the pivot at 68, so as to lock the link 62 in the position shown in Fig. 6 and hold the toggle members 35 and 36 in aligned position to retain the jaw 28 in its lowermost cable-engaging position.

By raising the handle 66 to swing the pivot 64 upward and around pivot 68 to the left, the link 62 will urge the toggle member 36 toward the left so as to break the joint 30 of 38 and permit the spring 34 to elevate the cable-engaging jaw 28. This movement is sufficient to so separate the jaws 24 and 28 as to permit insertion of the cable C therebetween. Movement of the handle 66 downward will then draw the pivot 38 to the position shown in Fig. 1 so as to align the members 35 and 36 and force the jaw 28 into cable-clamping position. As shown in Fig. 1, the pivots 66, 65 and 68 are substantially 40 in alignment, but the link is not yet in locked position, as it does not yet engage the lower wall 67 of the link-engaging groove, this position being also shown in Fig. 5. By further downward movement of the handle 66, the link 62 will be brought into engagement with said wall 67, bringing the pivot 64 beyond dead center, as above described, and thereby locking the link.

By lifting the pin 50 and rotating the 50 yoke 46 to the left in Fig. 1, the eccentric pin 42 will be lowered. This will reduce the space between the jaws 24 and 28 when in clamping position so as to engage a smaller cable. By swinging the yoke 46 to the right in Fig. 1, the eccentric pin 42 will be elevated so as to permit the clamping of a larger cable.

It will be noted from this construction that the handle 66 projects laterally from the casing 10 in the same direction in which the cable C projects. By this construction,

said handle 66 and cable C are substantially in the same vertical plane so that said handle is in a large measure protected by the cable when the bucket to which the grip is attached is in motion.

I claim:

1. An aerial tramway grip comprising a block, a pair of cable-engaging jaws on said block, one of said jaws being movable on the block, a toggle connected at one end with the movable block, and means to move the toggle to move the block, the other end of the toggle being pivoted on an adjustable pin whereby the clamping position of the movable jaw may be adjusted.

2. An aerial tramway grip comprising a block, a pair of cable-engaging jaws on said block, one of said jaws being movable on the block, a toggle connected at one end with the movable block, means to move the toggle to move the block, a pin on which the other end of the toggle is pivoted, and a rotary sleeve in which said pin is eccentrically mounted whereby rotation of the sleeve will produce adjustment of the clamping position of the movable jaw.

3. An aerial tramway grip comprising a block, a pair of cable-engaging jaws on said block, one of said jaws being movable on the block, a toggle connected at one end with the movable block, means to move the toggle to move the block, and a handle pivoted on the block and connected with said toggle for moving the same to and from clamping position, said handle and the engaging portions of said jaws extending in the same general direction whereby said handle will extend in the same general direction as a cable being gripped and the cable will serve 100 to guard the handle.

4. An aerial tramway grip comprising a block, a pair of cable-engaging jaws on said block, one of said jaws being movable on the block, a toggle connected at one end with the movable block, means to move the toggle to move the block, and a handle pivoted on the block and connected with said toggle for moving the same to and from clamping position, said handle and the engaging portions of said jaws extending in the same general direction whereby said handle will extend in the same general direction as a cable being gripped and the cable will serve to guard the handle, there being a link connecting with the toggle and pivoted on the handle, whereby the link may be thrown past dead center by the handle to lock the toggle in clamping position.

In testimony whereof I affix my signature.

EDWARD H. SACKETT.
